UNITED STATES PATENT OFFICE.

HENRY BOSCHEN, OF NEW YORK, N. Y.

BILLIARD AND POOL TABLE POCKET.

SPECIFICATION forming part of Letters Patent No. 257,917, dated May 16, 1882.

Application filed March 27, 1882. (No model.)

To all whom it may concern:

Be it known that I, HENRY BOSCHEN, of the city, county, and State of New York, have invented certain new and useful Improvements 5 in Billiard and Pool Table Pockets, of which the following is a specification.

The object of this invention is to furnish an improved pocket for billiard and pool tables, which pocket is readily expanded when a number 10 of balls are played into the same and contracted again when they are removed. The pocket shows instantly the balls collected therein, and can be manufactured with less material and consequently at a less cost than the pockets 15 heretofore in use.

The invention consists of a pocket for billiard and pool tables which is made of a leather blank that is cut by longitudinal lines of alternating slits so as to form an expandable 20 pocket. The blank is attached by means of shorter strips or fingers at its inner side and by longer exterior strips or fingers to the frame and irons of the billiard-table, and by means of short slots and a cord to a grooved ring 25 which forms the bottom of the pocket.

In the accompanying drawings, Figure 1 represents a top view, and Fig. 2 a vertical transverse section on line $x-x$, Fig. 1, of my 30 improved pocket for billiard and pool tables; and Fig. 3 is a plan view of a blank from which the same is made.

Similar letters of reference indicate corresponding parts.

Referring to the drawings, A represents the 35 blank from which my improved billiard and pool table pocket is made. The blank A is made of good tough leather of the form shown in Fig. 3, and provided with short slits a, that are arranged in lines parallel to the longitudinal center line of the blank, but in such a manner that the slits of adjoining lines alternate with each other. In this manner the blank, when applied for use, is capable of expansion as the slits of the blank allow the 40 pocket to spread in lateral direction to such an extent that a number of balls can be stored up therein. The leather blank A is applied by the strips or fingers $b b' b^2$, which are formed at the upper end to the frame and irons of the 45 table. The shorter fingers, b, are nailed to the

frame of the table, while the intermediate strips or fingers, b' , are nailed to the ends of the rails, and the exterior longer fingers, b^2 , are sewed to the leather covers of the irons let into the outer rail of the table, as shown in Fig. 2. Short slits e are cut into the strips or fingers d, at the lower edge of the blank A, through which slits a cord is passed for attaching the lower fingers, d, to the grooved ring f, that forms the bottom of the billiard-pocket. Around the lower strips, d, the ornamental bottom fringe of the pocket is applied. The inner edges of the blank are tied together in any suitable manner before it is applied to the table, so as to prevent the escape of the 65 balls at the inner side of the pockets. The pocket can take up a large number of balls, as it will readily expand accordingly and resume its original shape when the balls are removed, in which case the pocket is contracted by the 70 weight of the bottom ring.

By cutting the leather blank in the manner described a comparatively small piece of material furnishes a pocket of considerable size when expanded, which is more durable and 75 less easily torn or injured than the pockets heretofore in use.

I am aware that pockets for billiard and pool tables have been made from a perforated piece of sheet material, provided with fingers or pendants that are secured to the center ring, forming the bottom of the pocket, and I therefore do not claim this feature, broadly. These pockets, however, did not change their shape, while my pockets expand as the balls are 80 played in and contract when they are removed. This is the essential feature of my improved pocket, whereby it becomes more useful, handier, and more attractive.

Having thus described my invention, I claim 90 as new and desire to secure by Letters Patent—

1. As a new article of manufacture, a pocket for billiard and pool tables, constructed from a leather blank which is provided with longitudinal and alternating lines of short slits, 95 whereby the pocket is capable of expansion and contraction when in use, substantially as set forth.

2. A blank for billiard and pool table pockets, provided with parallel longitudinal lines 100

of slits, which slits alternate with each other, the blank having end fingers and strips of greater length at the middle than at the sides, substantially as set forth.

- 5 3. A blank for billiard and pool table pockets, having alternating longitudinal slits *a*, upper end strips or fingers, *b b' b²*, and lower fingers, *d*, having short slits *e*, substantially as specified.
- 10 4. A pocket for billiard and pool tables, constructed of a blank having alternating longitudinal slits, exterior longer strips or fingers,

and interior shorter strips or fingers at the upper edge for attachment to the rail and irons, and slotted fingers or strips at the lower edge for attachment to the bottom ring, substantially as set forth. 15

In testimony that I claim the foregoing as my invention I have signed my name in presence of two subscribing witnesses.

HENRY BOSCHEN.
